UNITED STATES PATENT OFFICE.

WILLIAM A. RADFORD, OF CHICAGO, ILLINOIS.

TOY.

Application filed May 2, 1924. Serial No. 710,523.

My invention relates to the arts of amusement, education, and selling, and more specifically to an improved cut-out serviceable in all three ways; first, as an amusement device pure and simple; second, as a source of education and information; and third, as an adjunct to a selling campaign.

One object of the invention is to provide a device capable of performing all services, 10 in which no one of the features is rendered less efficient by the presence of any of the others. Stated more specifically, the object is to have each feature contribute to the usefulness and the interest of the device.

Another object is to make the device useful and interesting to persons of all ages.

Another object is to provide sheet like means capable of being assembled to represent views of opposite sides of a solid object 20 on opposite sides of the assembled device, without any unsightly mismatching between the parts thus assembled.

Another object is to provide sheet like means capable of being assembled into an 25 attractive space replica of a complete street scene.

A further object is to provide a combined perspective and plan representation of a plurality of buildings, preferably houses, the 30 perspective having a back ground which indicates the appearance of the particular building when complete and its relative appearance in connection with other houses on a street.

Another object is to utilize as much as possible of the entire area of a simple rectangular sheet of material in forming such a 35 replica.

Further objects and advantages of the invention will become apparent as the description proceeds.

In the accompanying drawings:

Fig. 1 is a plan view of a short section of a blank according to my invention;

Fig. 2 is a perspective view of a street scene assembled from such blanks; and

Fig. 3 is a similar perspective showing the blanks arranged to portray one side of a street only.

In the embodiment of my invention selected for illustration, and with reference first to Fig. 1, I provide flat strips of material carrying indicia defining a space at 10 corresponding to half the width of a street, a parkway at 12, a sidewalk at 14, front yard at 16 extending back to a building line at 18,

buildings 20 shown in front view, and a surrounding mass of foliage 22. The space between the foliage 22 and the center line at 24 is utilized for a plurality of inserts 23 60 representing persons, motor cars, and many other various objects ordinarily seen along a street.

The foregoing areas comprise substantially half the sheet of material. On the other half I make a line 28 spaced from line 24 by a distance equal to the distance between lines 24 and 18. Measuring back from line 28 I portray a mass of foliage 30 having upper contour lines duplicating those of the 70 foliage 22, although the arrangement of foliage within the contour line need not necessarily be the same. In the foliage I show rear perspective views 32 of the same houses shown in front view at 20. Additional cut-outs 26 may be employed to utilize the space between foliage 30 and line 24. The parts thus far described may be utilized substantially as follows: The strip is preferably severed first along line 24, and next a cut is 80 made along the contour of foliage 22 and along the contour of foliage 30. The two halves may then be folded 90° about lines 18 and 28, and the foliage portions juxtaposed to stand upright. These portions may be pinned or preferably pasted together, and as the edges of the foliage 22 and 30 register, there will be no projecting blank surfaces to be seen when looking at the assembly from either side. Back of each house, 90 i. e., in the back yard of the lot as at 34, I provide a plan view of the house illustrated. The inserts 26 each comprise a figure portion 36 and a base portion 38, and may be cut out and folded to bring the base and 95 figure portions substantially to right angles, so that the figures may be positioned at various points along the street to complete the representation of a street scene. The contour of the front view of a house at 20 and a rear view of the same house at 32 would not register, but by providing a bank of foliage 100 for the front and rear and using the same contour line for the foliage, suitable registry is obtained, and an unsightly appearance 105 avoided.

According to the space available for using the devices, they may be assembled as in Fig. 2 to show both sides of a street, or as in Fig. 3 to show one side of a street of greater 110 length.

Very young children will find amusement

and no little intellectual training in merely looking at the devices, and in moving the figures 36 from place to place. Children of a more advanced age will receive manual training in cutting out, folding and pasting the devices. Still older persons will find the building plan at the rear of each house of no little interest, especially as attractive perspective views of the assembled house from 5 front and rear are close beside the plan. Comparison of the different houses shown by the devices with each other and with actual houses with which those discussing the matter are familiar is facilitated by this arrangement. In this way, all the members of 10 the family find something to interest them all at the same time in the same device, although the grounds of interest are different. While the parents and older children 15 are discussing the relative merits of different styles of architecture for a home, their presence will exert a disciplinary influence on the younger children, and at the same time they will not be burdened with 20 the feeling of merely attending on activities of the youngsters for that purpose only. One of the ways in which the article is intended to be used, is substantially as follows: The cut outs will be distributed gratis 25 to children by some one interested in selling building materials, services in landscape gardening, or architects' plans, and will preferably bear the name of the distributor in a conspicuous way. They will find their 30 way into every home in a neighborhood in a surprisingly short time, and in any home where a prospective customer is found the attractive display and the convenient presentation in compact form of a relatively 35 large amount of information cannot fail to attract much interest. Such a presentation 40 will be much better and more thoroughly digested than it could possibly be in a window

where the prospective customer must go and stand on the sidewalk to look at it; and 45 during the process the name of the advertiser will be deeply impressed in the memory.

Without further elaboration, the foregoing will so fully explain the gist of the invention, that others may, by applying current knowledge, readily adapt the same for use under various conditions of service, without eliminating certain features which may properly be said to constitute the essential items of novelty involved, which items are intended to be defined and secured to me 50 by the following claims.

I claim:

1. A cut-out comprising two blanks placed 55 back to back, said blanks having portions turned out at right angles to form a supporting base, a pictorial representation of a house on one blank and a pictorial house representation of the same house on the 60 other blank, said house representations being of different contour and the edges of each blank bearing representations of foliage surrounding each house representation and masking the differences in contour of the 65 house representations and providing registering edges about the two blanks of the 70 cut-out.

2. A cut-out comprising two sides placed 75 back to back, a view of an object on one side, a different view of the same object on the other side, said views having different contours, and pictorial representations of matter other than said object surrounding 80 each of said views and along the edges of each side for masking the differences in contour of said views and providing registering edges about the two sides of the cut-out.

In witness whereof, I hereunto subscribe my name this 28th day of April, 1924.

WM. A. RADFORD.
